EXPANDED METAL SHEET OR THE LIKE

Charles B. Alvord, Kenilworth, and Norbert O. Harz,
Park Ridge, Ill., assignors to United States Gypsum
Company, Chicago, Ill., a corporation of Illinois

Filed Oct. 24, 1958, Ser. No. 53,137

Term of patent 14 years

(Cl. D54—2)

Fig. 1 is a plan view of an expanded metal sheet or the like embodying our new design;

We claim:

The ornamental design for an expanded metal sheet or the like, substantially as shown.
